MECHANISM FOR DISENGAGING DRIVING GEARS

Robert W. Kaltenbach, Cleveland Heights, Ohio

Application December 11, 1929, Serial No. 413,312

14 Claims. (Cl. 74—7)

This invention relates to mechanism for disengaging driving gears, and for causing them to engage also. It is designed for use primarily in rail cars in which a self-propelling power plant is installed, as for instance locomotive cranes, pile drivers, and similar equipment. When cars of this sort are propelled by means other than their own power plants, as for instance when being hauled in a train, it is highly desirable to effect a thorough disengagement of the driving mechanism so that no accidental re-engagement can occur. The present invention is designed for that purpose.

One of the objects of the invention is the provision of a mechanism of this kind which can be readily and easily operated from a position at the side of the car, thereby avoiding the necessity for the operator to get beneath the car, that being a dangerous situation as well as an awkward and inconvenient one.

Another object is the provision of mechanism of this kind adapted to disengage from the car axles and their gears all other gears and shafts in the driving mechanism.

Another object is the provision of a mechanism in which the end thrust of the propeller shaft gear is taken directly into the shaft.

Another object is the provision of a means of this character so constructed that the meshing of the driving gears is unaffected by the amount of wear to which the gear teeth have been subjected.

Another object is the provision of operating mechanism actuatable from the side of the car and so mounted upon the car body that while the mechanism is in inoperative position vibration and the relative motion of the body and running gear of the car in rounding curves etc. will not damage the mechanism or cause it to interfere with the car driving mechanism.

A further object is the provision of a locking device to hold the driving gears in mesh, this device being urged automatically toward operative position when the gear shifting mechanism is swung toward its idle position, and being urged automatically toward inoperative position when the fastening mechanism is swung toward its operative position.

Other objects and features of novelty will appear as I proceed with the description of that embodiment of the invention which, for the purposes of the present application, I have illustrated in the accompanying drawings, in which

Figure 1 is a plan view, partly in horizontal

section; showing one embodiment of the invention.

Fig. 2 is a front elevational view, certain parts being shown in vertical section, substantially on the line 2—2 of Fig. 1, and

Fig. 3 is a side elevational view of a fragment of the car frame illustrating a hanger for the operating shaft which may be employed in connection with the invention.

In the drawings, the floor of a rail car is illustrated at 10, being shown as supported upon metal I-beams 11, 12 and 13 and upon a side bar 14 of the frame, these beams and this floor constituting a portion of the car body which in this case considerably overhangs the wheels 15 of the car. A portion only of one truck of the car is illustrated herein. It comprises a live axle 16 adapted to be mounted in suitable bearings which have been omitted from the drawings in order to avoid confusing the illustration. The car wheels 15 are secured to the axle in any suitable manner.

Loose upon the axle 16 there are collars 17 and 18 which constitute part of a bearing support 19, having spaced bearings 20 and 21 therein for a section 22 of the propeller shaft, the exposed end of this section being provided with a

keyway 23 or equivalent means for connection with another section 24 of the collar shaft, which in the present instance may be a universal joint.

The shaft 22 has a keyway 25 therein, by means of which the hub of a bevel gear 26 is

slidably and non-rotatably connected with the shaft. The gear 26 is adapted to mesh with a second bevel gear 27 fixed to the axle shaft 16.

In the operation of the car under its own power, driving force is transmitted by the propeller shaft 22 through its gear 26 and the gear 27 to the axle shaft 16 and its wheels 15. The forward end of the bearing support 19 may be sus-

pended from the car frame or body by hanger 28. This hanger, as shown in Fig. 2, comprises a pair of parallel rock shafts 70 and 71 which are connected together by links 72. When the

forward end of shaft 22 is swung to one side or the other by the travel of the car truck around a curve, the links 72 swing about their pivotal connections with the rock shaft 70.

Inasmuch as there is a longitudinal as well as a transverse movement produced by such swinging of the propeller shaft, the rock shafts 70 and 71 turn to accommodate the necessary longitudinal movement.

In so doing the vertical distance between the shafts 70 and 71 changes somewhat, raising or lowering the shaft 22. Similarly,

when the car springs yield in response to inequalities in the track, so that the distance between the axle 16 and the car body changes, there is a tendency for the outer bearing of the 5 propeller shaft to move longitudinally. The rock shafts 70 and 71 accordingly swing to provide such longitudinal movement. In so swinging the vertical distance between them again changes somewhat, raising or lowering the forward end of the propeller shaft. In both cases the horizontal movement as well as the vertical movement of the forward end of the propeller shaft is compensated for by universal joints and slip joints in the driving connections (not shown). When there is no horizontal movement however, either transversely or longitudinally, the forward end of the propeller shaft is held securely against direct vertical movement, inasmuch as the links 72 stand vertical and the rock 10 shafts 70 and 71 are in vertical alignment, whereby vertical pressure has little tendency to swing the parts of the hanger either transversely or longitudinally. Hence the driving reaction between the gears 26 and 27 which is imposed upon 15 the hanger in an almost vertical direction is absorbed, and this would not be the case were springs or other resilient connections substituted for the hanger described.

The hub of the gear 26 is threaded to form 20 a screw 29 which receives a nut 30, the latter having at its rear edge a flange 31 carrying a gear 32. A thrust collar 33 is secured to shaft 22 by a pin 34. The periphery of this collar extends between the flange 31 and a ring 35 that 25 is separated from the flange 31 by a spacer 36 and secured in position by bolts 37 extending through the flange, spacer and ring. The nut 30 therefore may turn upon the collar 33, but is held thereby against movement along its axis.

An integral extension 38 of the bearing support 19 carries a sleeve 39 in which is rotatably mounted a trunnion 40, a collar 41 being pinned to the upper end thereof to carry the weight of 30 the trunnion and its associated parts. Fixed 40 to the lower end of the trunnion 40 is a bearing sleeve 42 in which is rotatably mounted an operating shaft 43. On the inner end of this shaft I secure a bevel pinion 44 adapted to mesh with the gear 32. This pinion by its engagement with one end of the bearing sleeve 42 prevents longitudinal movement of the shaft 43 in one direction, while a collar 45 pinned to the shaft on the opposite end of the bearing sleeve prevents movement of the shaft in the opposite 45 direction. The trunnion bearing 39, is suitably inclined, as shown, in order to enable the shaft 43 to clear the bottom of the frame side member 14. It extends through a box-like hanger 46 that is adapted to support the outer end of 50 the shaft and is large enough to permit considerable movement of the latter in the up and down and sidewise directions, whereby rocking movements of the car body are not transmitted to the shifter mechanism through the operating shaft 43. The hanger 46 on one side thereof is supplied with a threaded stud 47 which is adapted to extend through a hole in one or the other of two brackets 48 and 49 which are bolted or riveted to the bottom of the frame side member 14. The stud 47 may be caused to project through one or the other of these holes, after which a nut 50 is threaded onto the stud and against the bracket 48 or 49, as the case may be, thereby supporting and holding securely 55 the hanger 46. The hanger has to be turned

over, that is through 180°, when it is removed from one bracket and secured to the other. The inoperative positions of the shaft 43 and hanger 46 are illustrated in dotted lines in Fig. 1, the position A of the end of the shaft being that which it takes in the normal operation of a car, that is to say when the latter is standing or travelling upon a straight track, while one of the positions B or C is assumed when the car is standing or travelling upon a track curved in one direction or the other. The outer end of the shaft 43 is squared to take a crank 51, by means of which the shaft may be rotated manually in either direction, thereby causing the pinion 44 to rotate the gear 32 and turn the nut 30, which causes the screw 29 and the gear 26 to travel longitudinally upon the shaft 22. End thrust upon the shaft 22 is taken by a thrust washer 52 arranged between the collar 33 and the bearing 21.

End thrust upon the gear 26 produces little or no tendency toward relative rotation between the screw 29 and nut 30, as this thrust must act along lines almost perpendicular to the threads of the screw and nut. However, when the car is being propelled under its own power, speed changes tend to cause such relative rotation. In starting, for instance, collar 33 tends to turn ahead of the gear 32, the latter possessing considerable inertia. Hence the screw 29 which is fixed with relation to the collar 33 tends to turn ahead of the nut 30. Upon slowing down or stopping, inertia tends to keep gear 32 rotating at its previous speed, while the brakes on the car tend to slow down or stop the shaft 22, thereby tending to cause the nut 30 to turn upon the screw 29. I prevent such relative rotation by means which I will now describe. 53 is a locking sleeve slidably mounted upon the exterior surface of nut 30 and held against rotation by a key 54 working in a keyway formed in the sleeve. On the outer side of the sleeve 53 there is a peripheral groove 55 within which shifter shoes 56 ride, these shoes being pivotally mounted upon the forked ends of a shifter lever 57 which is pivoted upon a bracket 58 riveted to or integral with the bearing support 19. The sleeve 53 is provided on one end with teeth or projections 59 which are adapted to be received within slots or sockets 60 in the rear side of gear 26, the corresponding position of the sleeve being indicated in dotted lines in Fig. 1. Such engagement, of course, locks the screw and nut together against rotation. The shifter lever 57 is operated through a connecting rod 61, slide 62 movable upon the rod, and coil springs 63 and 64 surrounding the rod and held under suitable tension thereupon by nuts and washers 65, 66 and 65', 66'. The rod 61 is pivotally mounted at 67 between lugs extending laterally from the bearing sleeve 42.

Operation. Assuming that the gear 26 is in the operative position illustrated in Fig. 1, and that the locking sleeve 53 is in the operative or dotted line position of that figure, and that the operating shaft 43 is in the inoperative or dotted line position of the same figure, and assuming further that the operator desires to retract the gear 26 to inoperative position, he then proceeds as follows. The nut 50 is removed from the stud 47, the outer end of the shaft 43 is grasped and the shaft with its hanger 46 is swung upon the trunnion 40 into the full line position, causing the teeth of pinion 44 to mesh with the teeth of gear 32. Should they at

first fail to mesh a slight rotation of the shaft 43 will enable them to do so. The hanger 46 is then turned over, that is through an angle of 180°, the stud 47 caused to enter the hole in bracket 48, and the nut 50 threaded down to support and hold the hanger rigidly in position. The movement of the shaft 43 in the direction indicated pushes rod 61 to the full line position, causing spring 64 to push against slide 62, thereby shifting lever 57 to the full line position and pulling locking sleeve 53 out of engagement with gear 26 into the full line position. Now the operator places crank 51 upon the squared end of shaft 43 and rotates the shaft in the proper direction to turn nut 30 onto screw 29, thereby withdrawing gear 26 from engagement with gear 27. This rotation is continued as far as possible, that is until the slots 60 engage with the teeth 59, thereby spacing the gears 26 and 27 a considerable distance apart, after which the shaft 43 is swung back to its idle position, illustrated in dotted lines in Fig. 1, and fastened to the bracket 49. This swinging movement of the shaft pulls upon the rod 61. However, the sleeve 53 is held against movement by the gear 26, which is then in its retracted position. The shift lever 57 is therefore also immovable, and consequently this pull upon the rod 61 has no effect other than to compress the spring 63. Now assuming that the operator desires to again bring the gear 26 into mesh with the gear 27, he unfastens the hanger 46 from bracket 49 and swings the shaft 43 to the full line position, securing it in that position as before explained. This movement relieves the tension upon spring 63. The crank 51 is then placed upon the squared end of shaft 43 and turned to cause the nut 30 to back off the screw 29. The screw with its gear 26 is thereby forced to travel forward until the gear meshes with gear 27. All of the parts are then in the position illustrated in full lines in Fig. 1. Now the operator again swings the operating shaft 43 back to its dotted line or idle position, thereby automatically shifting the sleeve 53 to its dotted line or gear locking position.

In connection with the springs 63 and 64 upon rod 61, it may be remarked that their use is not only necessary because of the inability of the sleeve 53 to slide forward when the gear 26 is retracted, but also this spring arrangement is beneficial in that it sets up a pressure between the locking sleeve 53 and the gear 26 to insure their remaining in engagement while the car is travelling, and further in that it provides a resilient connection between the shaft 43 and the sleeve 53 which compensates for relative movements produced by the relative movements of the axle 16 and the car body when the car is travelling around a curve.

The provision of pivotal mountings for the shaft 43 and the lever 57 in fixed positions upon the bearing support 19 insures perfect registration of the movable parts of the disengaging mechanism. This registration is not affected by the hanger 46, which has no mechanical connection with the shaft 43, and in fact is so much larger than the shaft as to permit free movement of the latter when necessitated by the relative motion of the car body and truck in transit.

Having thus described my invention, I claim:

1. In mechanism of the class described, an axle and a propeller shaft, gears on said axle and propeller shaft adapted to intermesh, one of said

gears carrying a screw rigidly connected therewith, a nut for said screw, means for mounting said nut rotatably in a fixed position axially, means for rotating said nut in either direction to cause axial movement of said screw, and means operatively connected with said rotating means for locking said nut against rotation relative to said screw. 80

2. In mechanism of the class described, an axle and a propeller shaft, gears on said axle and propeller shaft adapted to intermesh, one of said gears carrying a screw rigidly connected therewith, a nut for said screw, means for mounting said nut rotatably in a fixed position axially, means for rotating said nut in either direction to cause axial movement of said screw, said last named means comprising an operating shaft mounted to move into and out of operative position, and means automatically operated by the movement of said shaft for locking said nut against rotation relative to said screw. 85

3. In mechanism of the class described, an axle and a propeller shaft, gears on said axle and propeller shaft adapted to intermesh, one of said gears carrying a screw rigidly connected therewith, a nut for said screw, means for mounting said nut rotatably in a fixed position axially, a gear carried by said nut, a pinion adapted to mesh with said last named gear, means for moving said pinion into and out of mesh with said gear, means for rotating said pinion, and means set in motion by the movement of said pinion away from the meshing position for automatically locking said nut against rotation relative to said screw. 90

4. In a vehicle, a body, running gear comprising an axle and a propeller shaft arranged at right angles to each other, a bevel gear for said axle, a bevel gear keyed to slide on said propeller shaft adapted to mesh with said axle gear, a screw carried by the hub of said propeller shaft gear, a nut for said screw, means for mounting said nut rotatably in a fixed position axially, a bearing support for said propeller shaft, a trunnion in said support, an operating shaft, a bearing therefor carried by said trunnion, and gears on said operating shaft and nut adapted to mesh in one position of the operating shaft, whereby the rotation of the operating shaft is adapted to move said propeller shaft gear 105 toward or away from said axle gear. 115

5. In a vehicle, a body, running gear comprising an axle, a propeller shaft arranged at right angles thereto, a bevel gear for said axle, a bevel gear keyed to slide on said propeller

shaft adapted to mesh with said axle gear, a screw carried by the hub of said propeller shaft gear, a nut for said screw, means for mounting said nut rotatably in a fixed position axially, a bearing support for said propeller shaft, a 130

trunnion mounted in said support, an operating shaft, a bearing therefor carried by said trunnion, gears on said operating shaft and nut adapted to mesh in one position of the operating

shaft, whereby the rotation of the operating 140

shaft is adapted to move said propeller shaft gear toward or away from said axle gear, a locking sleeve keyed to slide upon said nut and adapted to move into locking engagement with

said propeller shaft gear, and means operatively 145

connected with said operating shaft tending to shift said locking sleeve to locking position when the operating shaft is swung to inoperative position.

6. In a vehicle, a body, running gear com- 150

- prising an axle, a propeller shaft arranged at right angles thereto, a bevel gear for said axle, a bevel gear keyed to slide on said propeller shaft adapted to mesh with said axle gear, a screw carried by the hub of said propeller shaft gear, a nut for said screw, means for mounting said nut rotatably in a fixed position axially, a bearing support for said propeller shaft, a trunnion mounted in said support, an operating shaft, a bearing therefor carried by said trunnion, gears on said operating shaft and nut adapted to mesh in one position of the operating shaft, whereby the rotation of the operating shaft is adaptable to move said propeller shaft gear toward or away from said axle gear, a locking sleeve keyed to slide upon said nut and adapted to move into locking engagement with said propeller shaft gear, and means operatively connected with said operating shaft tending to shift said locking sleeve to locking position when the operating shaft is swung to inoperative position, said last named means comprising a resilient element. 80
7. In mechanism of the class described, an axle and a propeller shaft, gears on said axle and propeller shaft adapted to intermesh, one of said gears being slidably keyed to its shaft and carrying a screw rigidly connected therewith, a nut for said screw, means for mounting said nut rotatably in a fixed position axially, means for rotating said nut in either direction to cause axial movement of said screw, a locking member non-rotatably mounted upon the external surface of said nut, and means for moving the locking member into and out of locking engagement with said last mentioned gear. 85
10. In mechanism of the class described, an axle and a propeller shaft, gears on said axle and propeller shaft adapted to intermesh, one of said gears being slidably keyed to its shaft and carrying a screw rigidly connected therewith, a nut for said screw, means for mounting said nut rotatably in a fixed position axially, means for rotating said nut in either direction to cause axial movement of said screw, locking means permanently carried by said nut and shiftable axially thereupon, and means for shifting said last mentioned means into locking 90 engagement with said gear, whereby the nut and last mentioned gear are held against relative rotation. 95
11. In mechanism of the class described, an axle and a propeller shaft, gears on said axle and propeller shaft adapted to intermesh, one of said gears being slidably keyed to its shaft and carrying a screw rigidly connected therewith, a nut for said screw, means for mounting said nut rotatably in a fixed position axially, means for rotating said nut in either direction to cause axial movement of said screw, locking means permanently carried by said nut and shiftable axially thereupon, and means for shifting said last mentioned means into locking 100 engagement with said gear, whereby the nut and last mentioned gear are held against relative rotation. 105
12. In mechanism of the class described, an axle and a propeller shaft, gears on said shafts adapted to intermesh, one of said gears being slidably keyed to its shaft and carrying a screw rigidly connected therewith, a nut for said screw, a collar fixed to the last named shaft, an annular tongue and groove rotatable connection between said collar and nut, and means for rotating said nut to move said slideable gear into and out of mesh with the other gear. 110
13. In mechanism of the class described, an axle and a propeller shaft, gears on said shafts adapted to intermesh, one of said gears being slidably keyed to its shaft and carrying a screw rigidly connected therewith, a nut for said screw, a collar fixed to the last named shaft, an annular tongue and groove rotatable connection between said collar and nut, a gear carried by said nut, a pinion, means for moving said pinion into and out of mesh with said last named gear, and means for rotating said pinion. 115
14. In mechanism of the class described, an axle and a propeller shaft, a gear fixed upon said axle, a gear keyed to slide upon said propeller shaft and adapted to mesh with said axle gear, means for sliding said propeller shaft gear into and out of mesh with said axle gear, said last named means comprising a screw carried by said propeller shaft gear and a nut for said screw, said nut being swivelly connected with said propeller shaft, a gear on said nut, and a pinion movable into and out of mesh with said last named gear for rotating said nut relatively to the screw when the propeller shaft is stationary. 120
- ROBERT W. KALTENBACH. 125
- 140
5. screw carried by the hub of said propeller shaft gear, a nut for said screw, means for mounting said nut rotatably in a fixed position axially, a bearing support for said propeller shaft, a trunnion mounted in said support, an operating shaft, a bearing therefor carried by said trunnion, gears on said operating shaft and nut adapted to mesh in one position of the operating shaft, whereby the rotation of the operating shaft is adaptable to move said propeller shaft gear toward or away from said axle gear, a locking sleeve keyed to slide upon said nut and adapted to move into locking engagement with said propeller shaft gear, and means operatively connected with said operating shaft tending to shift said locking sleeve to locking position when the operating shaft is swung to inoperative position, said last named means comprising a resilient element. 80
25. In mechanism of the class described, an axle and a propeller shaft, gears on said axle and propeller shaft adapted to intermesh, one of said gears being slidably keyed to its shaft and carrying a screw rigidly connected therewith, a nut for said screw, means for mounting said nut rotatably in a fixed position axially, means for rotating said nut in either direction to cause axial movement of said screw, a locking member non-rotatably mounted upon the external surface of said nut, and means for moving the locking member into and out of locking engagement with said last mentioned gear. 85
30. In mechanism of the class described, an axle and a propeller shaft, gears on said axle and propeller shaft adapted to intermesh, one of said gears being slidably keyed to its shaft and carrying a screw rigidly connected therewith, a nut for said screw, means for mounting said nut rotatably in a fixed position axially, a gear carried by said nut, a pinion, means for moving said pinion into or out of mesh with said last named gear, and means for rotating said pinion. 90
35. In a vehicle, a body, a running gear comprising an axle and a propeller shaft, gears on said axle and propeller shaft adapted to intermesh, means for advancing and retracting one of said gears to and from intermeshing position, said last named means having a separable connection comprising a rotatable shaft extending outwardly to the edge of the vehicle body, a movable mounting for said shaft adapted to be moved by the shaft upon body movement thereof between positions of making or breaking said separable connection, and means for hanging the outer end of said shaft from the vehicle body in either operative or inoperative position. 95
40. In a vehicle, a body, a running gear comprising an axle and a propeller shaft, gears on said axle and propeller shaft adapted to intermesh, one of said gears being slidably keyed to its shaft and carrying a screw rigidly connected therewith, a nut for said screw, a collar fixed to the last named shaft, an annular tongue and groove rotatable connection between said collar and nut, and means for rotating said nut to move said slideable gear into and out of mesh with the other gear. 100
45. In a vehicle, a body, a running gear comprising an axle and a propeller shaft, gears on said axle and propeller shaft adapted to intermesh, one of said gears being slidably keyed to its shaft and carrying a screw rigidly connected therewith, a nut for said screw, a collar fixed to the last named shaft, an annular tongue and groove rotatable connection between said collar and nut, a gear carried by said nut, a pinion, means for moving said pinion into and out of mesh with said last named gear, and means for rotating said pinion. 105
50. In mechanism of the class described, an axle and a propeller shaft, gears on said shafts adapted to intermesh, one of said gears being slidably keyed to its shaft and carrying a screw rigidly connected therewith, a nut for said screw, a collar fixed to the last named shaft, an annular tongue and groove rotatable connection between said collar and nut, a gear carried by said nut, a pinion, means for moving said pinion into and out of mesh with said last named gear, and means for rotating said pinion. 110
55. In mechanism of the class described, an axle and a propeller shaft, gears on said shafts adapted to intermesh, one of said gears being slidably keyed to its shaft and carrying a screw rigidly connected therewith, a nut for said screw, a collar fixed to the last named shaft, an annular tongue and groove rotatable connection between said collar and nut, a gear carried by said nut, a pinion, means for moving said pinion into and out of mesh with said last named gear, and means for rotating said pinion. 115
60. In mechanism of the class described, an axle and a propeller shaft, gears on said shafts adapted to intermesh, one of said gears being slidably keyed to its shaft and carrying a screw rigidly connected therewith, a nut for said screw, a collar fixed to the last named shaft, an annular tongue and groove rotatable connection between said collar and nut, a gear carried by said nut, a pinion, means for moving said pinion into and out of mesh with said last named gear, and means for rotating said pinion. 120
65. In mechanism of the class described, an axle and a propeller shaft, gears on said shafts adapted to intermesh, one of said gears being slidably keyed to its shaft and carrying a screw rigidly connected therewith, a nut for said screw, a collar fixed to the last named shaft, an annular tongue and groove rotatable connection between said collar and nut, a gear carried by said nut, a pinion, means for moving said pinion into and out of mesh with said last named gear, and means for rotating said pinion. 125
